WELLINGTON O. STETLER, OF BEAVERTOWN, AND J. WILLIAM KLINGLER,
OF MIDDLE CREEK, ASSIGNEES OF ONE-THIRD TO ANTHONY C. SIMPSON,
OF SELIN'S GROVE, PENNSYLVANIA.

CAR-COUPING.

SPECIFICATION forming part of Letters Patent No. 359,904, dated March 22, 1887.

Application filed January 11, 1887. Serial No. 224,033. (No model.)

To all whom it may concern:

Be it known that we, WELLINGTON O. STETLER and J. WILLIAM KLINGLER, citizens of the United States, residing at Beavertown and Middle Creek, in the county of Snyder, State of Pennsylvania, have invented certain new and useful Improvements in Car-Couplers, of which the following is a specification, reference being had therein to the accompanying drawings.

This invention has relation to car-couplers; and the object of the invention is to provide a coupler that will present the link thereof in a horizontal position to an approaching draw-head, that will automatically couple, and which shall prevent, to a great extent, the wearing of the link and pin one upon the other.

With these general objects in view the invention consists in certain features of construction hereinafter described, and particularly set forth in the claims.

Referring to the drawings, Figure 1 is a side elevation of a coupler constructed in accordance with our invention, the same being illustrated as coupled to a link. Fig. 2 is a plan view of the same, and Fig. 3 is a substantially vertical section, showing the parts in their relative position for coupling. Fig. 4 is a perspective of a catch employed for releasing the coupling-pin support, and Fig. 5 is a perspective of the spring-buffer inverted.

Like letters of reference indicate like parts in all the figures of the drawings.

A represents the draw-head, which may be of any usual and well-known construction, it being formed with the chamber A'.

Within the chamber A' is a buffer-block, B, the front face of which is concaved or cup-shaped, as at B', and provided with a pin-receiving recess, B². The top and bottom of this buffer may, if desired, be provided with guiding-flanges B³ B⁴, adapted to embrace the sides of the draw-head.

Interposed between the rear end of the buffer and rear wall of the recess A' (its ends bearing in recesses B⁵ A² in the buffer and draw-head, respectively) is a coiled spring, C, the tendency of which is to force the buffer

at its forward end against shoulders A³ at the mouth of the draw-head.

Mounted upon the draw-head in eyes A⁴ is a catching-frame, D, which consists of catching-arms D', the cross-bar D², and the lifting bail or loop D³. It is not necessary for the function of this catch-frame to perform that it be spring-pressed; but in this instance we have arranged a flat spring, D⁴, upon the top of the draw-head, so as to bear upon the cross-bar D² thereof. If desired, however, it is evident that the frame may be formed with coils at or near its journals. The catching-arms D' extend down, one at each side of the draw-head, and rest upon seats or recessed portions formed in the upper portion of the buffer and at each side thereof.

The arms D' may fall by gravity alone, if desired.

The draw-head is provided with the usual pin-holes, A⁵, at its top and bottom, and in this instance with a pin-guiding plate, A⁶, perforated for the reception of the pin, as at A⁷.

The operation of the invention is as follows: Referring more particularly to Fig. 3, which, as before stated, shows the relative arrangement of the parts when in the act of coupling, the link E enters the draw-head in the usual manner and comes in contact with the front face of the buffer B, which, being yieldingly pressed forward against the shoulders of the draw-head, is forced to the rear by said link. This act withdraws the buffer from under the pin F, which, falling by gravity, drops into the link, and the cars are coupled. Now comes an important feature of our invention. The buffer is forced back sufficiently to disengage itself from the catching-arms D' of the frame D, and by reason of these being spring-pressed (or it may be by gravity alone) they drop to the position shown in Fig. 1, interposing themselves in front of the buffer, and thereby preventing the spring C from forcing the same up against the end of the link and the link against the pin, whereby the two are constantly prevented from wearing and binding upon each other, as is usually the case where a spring-buffer alone is employed. This also allows

sufficient room for the link to work in while the cars are in motion.

Another advantage of our invention is, that by elevating the frame by its bail or a cord or chain attached thereto the buffer will be released, and will be forced by the spring to the front and against the end of the link; and by this movement of the parts the link will be caught and held firmly in a horizontal position, whereby it is sure to enter a companion draw-head of an approaching car.

By reason of the peculiar formation of the concaved buffer the link of an approaching car strikes against and is guided directly to its center and under the path of the pin, which, when released, as before described, positively enters the link and couples the cars.

Having described our invention and its operation, what we claim is—

- 20 1. The combination of a draw-head recessed and provided with a buffer, a spring interposed between the buffer and draw-head, and devices for retaining the buffer in a compressed or locked position free from contact with the link and pin, substantially as specified.
- 25 2. The combination of a draw-head recessed and provided with a buffer, a spring interposed between the buffer and draw-head, and spring-arms mounted on the draw-head and arranged to lock the buffer in a compressed position free from contact with the link and pin, substantially as specified.
- 30 3. The combination of a draw-head, recessed

as shown, with a spring-pressed buffer having guiding-flanges at its sides, substantially as specified.

4. The combination of a draw-head, recessed as shown, with a spring-pressed buffer having guiding-flanges at its sides and recessed seats, and with a catching-frame mounted upon the draw-head and adapted to retain the buffer in a compressed or locked position, substantially as specified.

5. The combination of the draw-head A, recessed, as at A' A², the buffer B, recessed, as at B² B⁵ B⁶, and the spring C, substantially as specified.

6. The combination of a draw-head, A, recessed, as at A', and having the buffer B, and spring C, with the catching-frame D, mounted upon the top of the draw-head and provided with the bail D³, cross-bar D², and arms D', substantially as specified.

7. The combination of the draw-head A, having the buffer B, recessed, as at B⁶, to form seats, with the frame D, having the bail D³, cross-bar D², and arms D', and with a spring, as D', substantially as specified.

In testimony whereof we affix our signatures in presence of two witnesses.
